UNITED STATES PATENT OFFICE.

EDMUND HARTUNG, OF JERSEY CITY, NEW JERSEY.

AUTOMATIC BUTTER-DISPENSER.

1,399,768.

Specification of Letters Patent. Patented Dec. 13, 1921.

Application filed March 30, 1921. Serial No. 457,094.

To all whom it may concern:

Be it known that I, EDMUND HARTUNG, a citizen of Poland, residing at Jersey City, in the county of Hudson and State of New Jersey, have invented certain new and useful Improvements in Automatic Butter-Dispensers, of which the following is a specification.

This invention relates to improvements in butter molders and cutters and has for its principal object to provide a device in which loose butter may be packed, and which will form said butter into squares ready for serving.

Another object of the present invention is to provide a compressor for packing the butter which advances step by step until the entire amount of butter contained within the forming chamber is forced outwardly after which the compressor may be released to return automatically to original position, preparatory to receiving an additional charge.

Still another object of the invention resides in the provision of a magazine in which the butter is supported prior to being manually forced into the press.

With these and other objects in view the invention consists of the novel construction, combination and arrangement of parts which will be fully set forth in the following specification, claimed and illustrated in the accompanying drawings, in which:

Figure 1 is a top plan view of this improved butter former.

Fig. 2 is a front view in elevation of Fig. 1.

Fig. 3 is an end view of the device.

Fig. 4 is a sectional view on line 4—4 of Fig. 2.

Fig. 5 is a view similar to Fig. 4 showing portions broken away to more clearly illustrate the details of construction.

Fig. 6 is a sectional view on line 6—6 of Fig. 2.

Referring to the drawings in detail the numeral 10 designates in its entirety the magazine into which the loose butter is placed, which magazine consists of a pair of rectangular bands 11 and 12, which are connected by a series of strips 13 and the end walls of the magazine 14.

Supported beneath said magazine is a trough 15 on the upper edges of which guide rollers 16 of the compressor 17 are adapted to engage. As illustrated in the drawings the upper side of the trough is open to re-

ceive the contents of the magazine 10, and it will be obvious that matter pressed from the magazine into the trough may then be forced by the compressor 17 through an outlet opening 18 formed in a die plate 19, arranged at the end of the trough.

Suitable outwardly extending flanges 20 are formed on the plate and surround the opening 18 to provide shearing edges for a purpose to be more fully hereinafter described.

Secured adjacent the rear end of the trough is a bracket 21 in which the rear end of a worm shaft 22 is rotatably mounted. The forward end of said shaft is journaled in the plate 19 near the opening 18, and carries a spur gear 23 which is arranged to mesh with an intermittent gear mounted for rotation with a shaft 25 the outer end of which is provided with a hand wheel 26. Slidably mounted on the worm shaft 22 is a block 27 provided near opposite ends with inwardly extending pins 28 adapted to engage in the groove of the shaft 22 so that as said shaft is rotated the block will be advanced. A suitable connecting member 29 connects the block with the compressor 17 and it will thus be seen that as the wheel 26 is rotated the gear 23 will be intermittently rotated so as to advance the compressor step by step.

In order to sever the proper quantity of butter from the main body, an arm 30 is carried by the shaft 25 and extends radially therefrom, and the outer free end of said arm is provided with an inwardly extending member 31 to which is secured the outer end of a cutting wire 32, the inner end of which is attached as at 33 to the intermittent gears 24.

In order to return the compressor to original position, a volute spring 34 is arranged adjacent one end of the shaft 22, and the inner end of said spring is attached to the shaft while the outer end may be secured to the side of the trough 15. A ratchet wheel 35 is secured to the shaft and pivotally mounted for co-operation with said ratchet wheel is a pawl 36 which is arranged to prevent the reverse rotation of the shaft under the influence of the spring 34.

After a charge of butter has been forced from the trough and it is desired to return the compressor to original position, the pawl 36 may be released and the shaft 22 will rotate in a direction to withdraw the compressor. It will be understood if so desired a

suitable buffer spring 37 may be arranged at the rear end of the shaft 32 so that as the block 27 is moved rearwardly it will not forcibly strike the bracket 21.

- 5 In use it will be seen that upon rotating the hand wheel 26 the teeth of the intermittent gear 24 will engage the teeth of the gear 23 to cause the same to rotate in a direction to advance the compressor and the 10 butter contained in the trough between the compressor and the plate 19 will be forced outwardly through the opening 18 so that when the wire 32 passes across the flange 20, that portion of the butter projecting 15 beyond the flange will be severed thus forming a square of butter ready to be served.

While in the foregoing there has been shown and described the preferred embodiment of this invention it is to be understood 20 that certain minor changes in the details of construction, combination and arrangements of parts may be resorted to without departing from the spirit and scope of the invention as claimed.

25 I claim:

1. A device of the class described com-

prising a trough, a compressor operable within the trough to force matter contained in said trough through one end of said trough, means to intermittently advance the 30 compressor, means associated with the advancing means for severing that portion of the contents of the trough forced beyond its end and means for permitting the compressor to automatically return to withdrawn 35 position.

2. A device of the class described comprising a magazine, a trough supported beneath said magazine and adapted to receive the contents thereof, a compressor within the 40 trough, one end of said trough being open, means to intermittently advance the compressor toward the open end of the trough, a severing wire adapted to sweep the open end of the trough, to cut that portion of the 45 contents of the trough forced beyond its end from the portion of the contents remaining in the trough, and automatic means for withdrawing the compressor.

In witness whereof I affix my signature. 50

EDMUND HARTUNG.
